CHILD'S SWING

Eugene C. Schmidli, Minneapolis, Minn.

Application August 28, 1948, Serial No. 148,357

Term of patent 7 years

(Cl. D15—11)

To all whom it may concern:

Be it known that I, Eugene C. Schmidli, a citizen of the United States, residing at Minneapolis, county of Hennepin, and State of Minnesota, have invented a new, original, and ornamental Design for a Child's Swing, of which the following is a specification, reference being had to the accompanying drawing, forming a part thereof.

Fig. 1 is a top plan view, showing my new design for a child's swing.

Fig. 2 is a side elevational view of the swing; Fig. 3 is a front elevational view thereof; and Fig. 4 is a front perspective view of the swing.

I claim:

The ornamental design for a child's swing, as shown.

EUGENE C. SCHMIDL.
